UNITED STATES PATENT OFFICE.

SAMUEL KROSS, OF MEMPHIS, TENNESSEE, ASSIGNOR OF SEVENTY-FIVE ONE THOUSANDTHS TO LOUIS FRY, OF NATCHEZ, MISSISSIPPI.

RUG AND METHOD OF MANUFACTURE.

1,191,847.

Specification of Letters Patent. Patented July 18, 1916.

Application filed August 24, 1915. Serial No. 47,103.

To all whom it may concern:

Be it known that I, SAMUEL KROSS, a citizen of the United States, residing at Memphis, in the county of Shelby and State of Tennessee, have invented certain new and useful Improvements in Rugs and the Method of Manufacture; and I do hereby declare the following to be a full, clear, and exact description of the invention, such as 10 will enable others skilled in the art to which it appertains to make and use the same.

This invention relates to rugs and like fabrics and the process of weaving the same, and has for an object to provide a rug of 1 the tufted variety, each tuft of which is tied by an integral knot about the warp thread.

A further object of the invention is to employ the tufting thread of the fabric in such manner that each individual tuft is 20 attached directly to a warp thread or a plurality of warp threads by an integral knot embracing such threads preventing thereby the thread of the tuft from being pulled out.

25 With these and other objects in view the invention consists in certain novel features of construction, combination and arrangement of parts as will be hereinafter more fully described and claimed.

30 In the drawings:—Figure 1 is an enlarged view of a tufting loop and the knot by which it is knotted to the warp thread. Fig. 2 is a perspective view showing a few warp threads crossed by weft threads, and 35 the manner of starting the tufting yarn.

Figs. 3 to 11 inclusive are diagrammatic views showing the progressive steps of forming the loop and knot. Fig. 12 is a view in side elevation of two of the loops with the 40 looping bars positioned therein. Fig. 13 is a perspective view of a number of the knots located upon their warp threads with a number of weft threads in position to hold the knots and form the fabric. Fig. 14 is a 45 view in elevation of two of the loops severed to form a velvet pile. Fig. 15 is a view of a battery of the looping fingers seen in edge elevation. Fig. 16 is a view of one of the looping fingers in side elevation.

50 Like characters of reference designate corresponding parts throughout the several views.

It is well known that in forming a pile or tufted fabric it is customary to insert the piling or tufting thread upwardly 55 through the fabric, either through the completed fabric or through the fabric as it is being woven, and that in the latter case the tufting is sometimes inserted through twisted pairs of warp threads or other means 60 are employed for retaining the loops of the tufts in position while the weft threads are coincidentally being woven into place.

In the present invention the process includes the forming of the tufts while the 65 fabric is being woven, and the tufts are formed upon and about the warp threads, the weft threads being coincidentally woven into place for the purpose of retaining the knots and forming the fabric as above described. The present invention is adapted to be used with any form of loom embodying means for holding the warp threads, a harness and a beater. None of the loom mechanism is shown in the drawings, as it 70 forms no part of the method of producing the knotted tufts. As shown in the drawings, the warp threads 20 are to be understood as passing from the beam through the harness and the reed—all in substantially the usual and ordinary manner. Also the weft threads 21 are woven into the warp threads in substantially the usual and ordinary manner as the warp threads are moved by the harness. 80

To start the present fabric, a plurality of the weft threads 21 are woven into the warp threads as shown at Fig. 2 and the tufting yarn 22 is woven in simply to hold the ends. Each of the tufting threads 22 is threaded 90 through the eye 23 of the loopers 24, one of which is provided for each of the tufting threads, such loopers being secured together as shown at Figs. 15 and 16, or formed or connected in any approved manner. The 95 battery of loopers each with its accompanying thread is located below the warp, and is moved upwardly in any approved manner in timed relation to the action of the balance of the parts. The normal position of 100 the loopers 24 is shown at Figs. 2 and 3, the tufting threads 22 coming from any convenient source, and preferably though not necessarily passing through the harness, but

of course not through the eye of the harness so that it is not affected by the movement of the harness.

The first upward movement of the loopers 24 as shown at Fig. 4, moves the tufting thread 22 upwardly between two of the warp threads to form the loop 25. Coincidentally with the movement of the loopers 24 upwardly the fingers 26 descend. The fingers 26 are made up substantially the same as the loopers 24, with eyes 27 in their lower extremities. The upward movement of the loopers 24 and the downward movement of the fingers 26 is such that the lower extremities of the fingers 26 come between the loop 25, as shown at Fig. 4. While in this position a rod 28 is inserted through the eye 27 and through the loop 25, which prevents the loop 25 from following the loopers 24 as it descends to the position shown at Fig. 6, once more below the line of the fabric and below the warp threads 20. While in this position below the warp threads the loopers are shogged laterally to the position shown in dotted lines at Fig. 7, the fingers being simultaneously shogged so that the loop 25 now stands inclined to the vertical. While in this inclined position the loopers are again inserted upwardly between the warp threads, but this time passed through adjacent openings or between other pairs of warp threads so that a loop 29 is formed about one or more of the warp threads.

35 The upward movement of the looper 24 through the loop 25 forms a loop 30 inserted through the loop 25 as shown at Fig. 8. In this position, with the loop 30 above the warp and inserted through the loop 25, the tufting bar 31 is inserted through the row of loops 30 as shown at Fig. 9. After the tufting bar 31 is inserted through the loops 30 the rod 28 is withdrawn from the loop 25, and the looper 24 is drawn downwardly through the warp. At this point tension is applied to the tufting yarn in any well-known manner so that the descent of the looper 24 serves to draw the tufting yarn 22 over the tufting bar 31 to draw the loop 25, as shown successively at Figs. 10 and 11, into the form of a knot around the base of the loop 30 as shown at Figs. 12, 13 and 14. In this position the loopers 24 and fingers 26 are shogged back to original position, and meantime any desired number of weft threads are woven into the warp so that the next loop is started embracing not only the warp threads but also the weft threads as shown at Figs. 12 and 14.

60 It will be perfectly apparent that the tufting bar 31 being formed with the usual and ordinary groove 32 along its upper edge is employed as in the usual and ordinary manner to slide a knife along such groove to slit the upper end of the loops as shown at

Fig. 14. Even after the loop is slit the two threads which formerly constituted the loop are securely tied to one or more of the warp threads, and adjacent tufts are connected by loops embracing the weft threads. ⁷⁰

Throughout the specification mention has been made of forming the knot about one or more of the warp threads. It is to be understood, of course, that any number of warp threads may be run through a single reed and be operated upon as a single warp thread. The tufting yarn has also been referred to in the singular, but it is obvious that any number of threads may be combined to take the place of the single tufting thread shown in the drawings. ⁷⁵

By the practice of the aforesaid method a rug is produced, each tuft of which is tied to a warp thread by a knot formed upon the upper side of the warp thread and interwoven with the weft thread so that it becomes impossible for any one of the tufting threads to pull out. ⁸⁰

I claim:

1. The method of forming a rug consisting in employing adjacent warp threads, inserting a loop of tufting thread upwardly upon one side of a warp thread and retaining it in such elevated position, passing a loop of the same warp thread upwardly upon the opposite side of the warp and inserting it through the first-mentioned loop to form a second loop, retaining the last-mentioned loop in elevated position and releasing the first-mentioned loop, and drawing the first-mentioned loop taut about the second-mentioned loop. ⁹⁰

2. The method of forming a rug consisting in employing a plurality of parallel warp threads, inserting a loop of tufting thread upwardly upon corresponding sides of the several warp threads, retaining the upwardly inserted loop from withdrawal downwardly, forming a second loop upon the opposite sides of said several warp threads and inserting said second loop through the first-mentioned loop, retaining the second-formed loop against withdrawal and releasing the first-mentioned loop, exerting tension upon the tufting thread to draw the first-formed loop into a knot about the base of the second-formed loop, and weaving weft threads into the warp threads in juxtaposition to the knot. ¹⁰⁵

3. A rug comprising a plurality of warp strands, tufting loops extending upwardly from some of the warp strands, and an integral knot formed about the base of each of the tufts in juxtaposition to the warp and knotting the tuft to a single warp strand. ¹²⁰

4. A rug comprising a plurality of tufts composed each of two upwardly extending adjacent yarn extremities, and a knot integral with one only of such extremities formed as an extension from one side of the ¹²⁵

tuft loop knotted about the adjacent bases of both such extremities.

5. A rug comprising a plurality of warp threads, tufting threads extending upwardly from some of the warp threads, and a loop integral with one only of the tufting threads formed as an extension from one side of the loop forming a knot about the base of both

such tufting threads and embracing the warp thread.

10 In testimony whereof I affix my signature in presence of a witness.

SAMUEL KROSS.
